UNITED STATES PATENT OFFICE.

HAROLD A. BAUM, OF CHICAGO, ILLINOIS, ASSIGNOR TO THE SAFETY ELECTRIC COMPANY, OF CHICAGO, ILLINOIS, A CORPORATION OF ILLINOIS.

DESIGN FOR AN ELECTRIC-LAMP BULB.

Application filed June 19, 1922. Serial No. 2,735. Term of patent 3½ years.

To all whom it may concern:

Be it known that I, HAROLD A. BAUM, a citizen of the United States, residing at Chicago, in the county of Cook and State of Illinois, have invented a new, original, and ornamental Design for Electric-Lamp Bulbs, of which the following is a specification, reference being had to the accompanying drawing, forming part thereof.

The drawing is an elevation of an electric lamp bulb, showing my new design.

I claim:

The ornamental design for an electric lamp bulb, as shown.

HAROLD A. BAUM.
